UNITED STATES PATENT OFFICE.

WILLIAM W. BEWSIC, OF ELYRIA, OHIO.

UNDERWAIST.

SPECIFICATION forming part of Letters Patent No. 758,892, dated May 3, 1904.

Application filed July 1, 1903. Serial No. 163,852. (No model.)

To all whom it may concern:

Be it known that I, WILLIAM W. BEWSIC, a citizen of the United States, residing at Elyria, in the county of Lorain and State of Ohio, have invented a certain new and useful Improvement in Underwaists, of which the following is a full, clear, and exact description, reference being had to the accompanying drawings.

10 This invention relates to that type of underwaist comprising, essentially, a waistband and suitable shoulder-supports therefor, such as is illustrated in Patent No. 630,157, granted August 1, 1899, to Eva M. Worth.

15 The object of the present invention is to provide such an underwaist in a form which shall be neat in appearance, durable in service, and very cheap to construct. The features of construction by which I accomplish this are 20 hereinafter fully described, and are particularly set out in the claims.

In the drawings, Figure 1 is a perspective view of the underwaist. Fig. 2 is an enlarged and somewhat-exaggerated cross-section on 25 the line 2 2 of Fig. 1. Fig. 3 is a similar cross-section on the line 3 3 of Fig. 1.

Referring to the parts by letters, A A' designate partial waistbands, being adapted to be buttoned together by the buttons *a* to form 30 the complete band. Such waistband carries buttons *a'* for supporting the skirt. Two shoulder-bands B B rise from the band A, being secured at their lower ends to it close together. As they rise they spread apart, leaving a V-shaped opening between them. After 35 passing sufficiently high for the shoulders the bands descend similarly and come together at their lower ends, where they are secured to the waistband A'. Occupying the lower portions of the V-shaped spaces between the two bands B B are the gussets C, one at the front and one at the back. The edges of these gussets are reinforced by strips *c*. Extending from the shoulder-bands to the waistbands are 40 diagonal supporting-strips D.

In order to make the waist cheaply enough to be marketable, it is essential that it be so devised that as many sewing operations as possible may be carried on at once. To allow 45 this to be done, I make the bands B each of

two separate thicknesses of cloth, as indicated in Fig. 3. The edge of each thickness is turned inward, as at *b*, and a single row of stitches *b'* is made near each edge of the band through the four thicknesses of cloth thus presented. The bands B are the same width throughout, and this enables the two seams *b' b'* on each band to be made at the same time by a machine employing two needles. While the band B is being sewed, the gusset C and the diagonal strip D are each inserted, and the same stitches pass through them, as illustrated in Fig. 2. By this operation the cost of construction is greatly reduced, while the neatness of the waist is very much increased over 55 what it would be if the gusset-pieces C were sewed onto one of the external faces of the bands B or over what it would be if the band B were made of a single piece of doubled cloth cut at its doubled edge for the insertion of the 60 gusset-piece or the diagonal strip.

The weight on the waist comes directly on the strong double-thick shoulder-straps. Any tendency to tear along the gusset is overcome by the double reinforcement formed by the 75 two strips *c*, which cross at the point where the strain is greatest and then continue and extend into the bands B. The whole construction makes a waist which by thorough trial has been shown to be extremely strong as well 80 as being light and graceful in appearance.

Having described my invention, I claim—

1. An underwaist comprising a waistband and shoulder-straps connected thereto, the shoulder-straps being made of double thicknesses of cloth stitched together at their edges by parallel seams, there being between the bands a piece extending between the two plies of each band, substantially as described. 85

2. An underwaist comprising a waistband and shoulder-straps connected thereto, the shoulder-straps being made of double thicknesses of cloth stitched together at their edges, there being between the bands a piece extending between the two plies of each band, and 90 there being diagonal supporting-strips extending upward from the waistband and taking between the two plies of the shoulder-straps, substantially as described. 95

3. An underwaist comprising a waistband 100

and shoulder-straps connected thereto, the shoulder-straps being made of double thicknesses of cloth stitched together at their edges, there being between the bands a gusset-piece 5 extending between the two plies of each band, the upper edge of the gusset-piece being V-shaped, and there being a pair of reinforcing-strips extending along the edges of the gusset-piece, and crossing each other and continuing to the shoulder-straps, substantially as described.

4. In an underwaist, the combination of a waistband and a pair of diverging cloth bands secured thereto close together at their lower 15 ends and gradually separating as they extend upward, each band having its sides parallel and being composed of two thicknesses of cloth with the edges folded inward upon themselves, two rows of stitching for each band 20 through said turned-in edges, and a gusset between the bands extending thereinto, the inner rows of stitching of said two bands passing also through the edge of the gusset inside said bands, substantially as described.

5. In an underwaist, the combination of a waist member and a pair of diverging cloth bands secured thereto close together at their lower ends and gradually separating as they extend upward, each band being composed of 25 two thicknesses of cloth with the edges folded inward upon themselves, two rows of stitching for each band through said turned-in edges, a gusset between the bands and extending thereinto, diagonal supporting-strips on 30 the outer sides of the bands connecting them with the waist members, the inner rows of 35 stitches of said two bands passing also through

the edge of the gusset inside said bands, and the outer row of stitches passing also through the upper ends of the diagonal supporting-strips and inserted between the two plies of 40 said cloth bands at their outer edges, substantially as described.

6. In an underwaist, the combination of a waist member and a pair of diverging cloth bands secured thereto close together at their lower ends and gradually separating as they extend upward, each band being composed of two thicknesses of cloth with the edges folded inward upon themselves, two rows of stitching 45 for each band through said turned-in edges, a gusset between the bands and extending thereinto, diagonal supporting-strips on the outer sides of the bands connecting them with the waist members, the inner rows of 50 stitches of said two bands passing also through the edge of the gusset inside said bands, and the outer row of stitches passing also through the upper ends of the diagonal supporting-strips and inserted between the two plies of 55 said cloth bands at their outer edges, the upper edge of the gusset-piece being V shape and there being a pair of reinforcing-strips extending along these upper edges of the gusset-piece and crossing each other and continuing along the surface of the gusset-piece, the ends of the reinforcing-strips being sewed 60 into the said cloth bands.

In testimony whereof I hereunto affix my signature in the presence of two witnesses.

WILLIAM W. BEWSIC.
